FILING DEVICE

Fred J. Kline, Bayville, N. Y., assignor to Acco Products, Inc., Long Island City, N. Y., a corporation of New York

Application February 2, 1932. Serial No. 590,368

6 Claims. (Cl. 129—16)

This invention relates to filing devices and more particularly to convenient and inexpensive equipment for filing drawings and similar sheets.

Drawings such as those used by architects, builders and engineers, are commonly rolled and disposed in a corner of the room where they are used. There they accumulate dust and dirt and are frequently torn or disfigured. Sometimes the drawings are stored flat in drawers, but it is practically impossible to index them satisfactorily, and they are not readily accessible. The difficulties involved in filing drawings are particularly marked in respect to the relatively fragile tracings which are employed to permit duplication of the drawings in the form of blueprints.

It is the object of the present invention to provide a simple and effective filing device in which drawings and similar sheets and particularly fragile tracings are suspended and from which they can be removed quickly and conveniently.

Other objects and advantages of the invention will be apparent as it is better understood by reference to the following specification and accompanying drawings, in which

Fig. 1 is a view in perspective of a device embodying the invention, showing the sheets suspended thereon;

Figs. 2, 3 and 4 are details in section, plan and in elevation respectively of the means for releasably securing the sheets to the hanger;

Figs. 5 and 6 are details in section and plan respectively of a modified form of the sheet fastening means;

Figs. 7 and 8 are details in section and plan respectively of another form of the sheet fastening means;

Figs. 9 and 10 are vertical and plan sections of another form of the sheet fastening means;

Figs. 11 and 12 are a section and plan respectively of another form of the sheet fastening means;

Figs. 13, 14 and 15 are vertical sections and a perspective view illustrating another form of the sheet fastening means;

Figs. 16, 17 and 18 are perspective and vertical sections of another form of the sheet fastening means;

Fig. 19 is a sectional view illustrating the operation of the device illustrated in Figs. 16 to 18, inclusive;

Figs. 20 and 21 are perspective views illustrating another form of the sheet fastening means;

Fig. 22 is a section illustrating the operation of the device as illustrated in Figs. 20 and 21; and

Fig. 23 is a fragmentary view in perspective of a sheet with a binder strip attached thereto.

In carrying out the invention, I may employ any suitable hanger, but prefer a strip of suitable material such as metal which may be detachably mounted upon a support. Conveniently the support may be pivoted upon a bracket adapted to be mounted upon a wall or on a suitable standard. The invention may be used, for example, in connection with cabinets and equipment such as is illustrated in my Patent No. 1,867,153, dated July 12, 1932. The invention is not limited to the particular details of equipment illustrated in that patent, as numerous variations of the supporting means for the hanger can be employed.

As an example of the invention, however, I may use a suitable bracket, preferably a channel member 5 having openings in the flanges thereof to receive a pin 6. The pin passes through a hinge member 7 at the end of a suitable support in the form of a projecting arm 8. This arm may be formed from a strip of metal, and is stiffened preferably by beads 9 stamped from the body thereof. To one of the beads 9 I may secure a supplemental arm 10 by welding, riveting or otherwise, thus providing a ledge to cooperate with the turned edge 11 of a hanger 12. The hanger may be formed of any suitable material, preferably sheet metal, so as to slidably engage the supplemental arm 10. Thus the hanger is pivotally supported on the bracket 5 and is slidably adjusted on the supplemental arm 10. The hanger can be removed bodily from the supplemental arm by merely lifting it or by sliding it. The parts described are simple and can be readily assembled. A number of hangers can be supported in parallel relation and pivotally on the bracket 5, and the file can be expanded consequently to support any desired number of drawings or similar sheets.

The invention is designed particularly to permit ready access to any particular sheet of a group suspended on the hanger, and I provide, therefore, on the hanger two or more members adapted to register with openings in the sheets and to receive and support a group of sheets 13 as indicated in the drawings. The means provided is so arranged as to permit the selection of any desired sheet, the separation of the group of sheets, and the removal of the particular sheet desired. The means employed may be embodied in various forms, and a number of modifications thereof are illustrated in the drawings.

Preferably the means engaging the openings in the sheets are tilted to avoid any tendency for

100

105

110

sheets to slip therefrom when the device is manipulated to remove one or more sheets. The tilting may be effected by bending the lower edge of the hanger slightly or by setting the sheet 5 engaging means at an angle in the hanger. Thus the sheets tend to gravitate toward the hanger even when not securely fastened.

Referring to Figs. 2 to 4 inclusive, I secure tubular members 14 to the hanger 12 in spaced 10 relation and projecting from one side thereof. The members 14 are tilted outwardly and upwardly as shown for the purpose heretofore mentioned. Each tubular member is provided with an internal thread 15 to receive the threaded end 15 16 on a co-operating member 17 which is adapted to be disposed within the tubular member 14. A head 18 on the member 17 facilitates manipulation thereof. When the member 17 is introduced in the member 14 and turned, the threads 20 lock the two members in assembled relation and the group of sheets 13 supported on the tubular members 14 are thus securely held thereon.

When a selected sheet is to be removed, the group of sheets in front thereof is moved backwardly and the members 17 are released and withdrawn, carrying this group of the sheets and leaving the selected sheet and the remaining sheets of the group supported on the members 14. The selected sheet can then be withdrawn 25 from the members 14, after which the members 17 can be replaced, all of the sheets of the group except the one removed being thus returned to the file. To replace the sheet removed, the operation is repeated and the sheet is inserted in 30 the file in its proper place.

In Figs. 5 and 6, the tubular members 19 are secured to the hanger 12 and are provided at their ends with resilient fingers 20. The co-operating members 21 having heads 22 are provided also with grooves 23 to receive the ends 40 of the fingers 20. Thus when the members 21 are inserted in the tubular members 19, they are locked in position but can be withdrawn readily by exerting a slight pressure upon the heads 22.

In Figs. 7 and 8, substantially the same structure is employed except that the locking is accomplished by a bayonet joint. Thus the tubular members 24 are mounted on the hanger 12 and the co-operating members 25 with heads 26 are shaped to fit closely within the tubular members 24, which may be provided with slots 27 to receive pins 27' on the members 25. In the operation of this device, the members 25 are turned 50 to release the pins 27' and are withdrawn by exerting suitable pressure on the heads 26. Access to the material in the file is obtained as in the preceding embodiments of the invention.

In Figs. 9 and 10, I have illustrated a device 60 including a latch to hold the members in assembled relation. Thus the hanger 12 is provided with projecting tubular members 28, and co-operating members 29 with heads 30 are provided with latches 31 pivoted at 32 with projecting ends 33. The latches 31 have downwardly projecting lugs 34 which are adapted to engage openings 35 in the tubular members 28. The members 29 may be released by lifting the projections 33, thus releasing the latches. The operation of removing and inserting sheets in the 65 file is accomplished as in the preceding embodiments of the invention.

In Figs. 11 and 12, the hangers 12 are provided with projecting tubular members 36 having 70 slots 37 in their upper faces. Co-operating

members 38 and are adapted to be inserted in the tubular members and are provided with heads 39 and notches 40, the notches being adapted to engage lugs 41 on the tubular members. Thus, when the co-operating parts are in the position indicated in the drawings, they are locked in assembled relation, but by merely lifting the heads 39 the members 38 can be freed and withdrawn to facilitate access to the sheets in the file.

In Figs. 13 and 15 inclusive, a similar device involving a slightly different principle of operation is illustrated. The hangers 12 are provided with projecting tubular members 42 having openings 43 therein. Within the tubular members 42 plunger 44 are disposed, the plungers having corresponding openings 45. Keys 46 with heads 47 and notches 48 co-operating with lugs 49 on the plungers 44 permit rotation of the plungers. With the plungers in the position indicated in Fig. 13, the keys 46 can be inserted, air being expelled through the openings 43 and 45. If then the plungers 44 are turned slightly in either direction, the openings 43 and 45 no longer register. They may, for example, take the position 100 indicated in Fig. 14. Air cannot then enter, and consequently an attempt to remove the keys 46 results in the formation of a partial vacuum which resists the movement of the keys. The latter are, therefore, locked in the closed position 105 until they are rotated sufficiently to cause the openings 43 and 45 to again register.

In Figs. 16 to 19 inclusive, I have illustrated another form of the invention adapted more particularly to co-operate with sheets having slots 110 communicating with the openings therein, as illustrated more particularly in Fig. 23. Thus, a sheet such as a blueprint 50 may be provided with a binder 51 having openings 52 and communicating slots 53.

To suspend such sheets, I mount upon the hanger 12 a plurality of members 54 having upturned ends 55 and 56 and adapted to be rotated. The positions of the members 54 may be limited by lugs 57 and 58 struck up from the body of 120 the hanger 12. The sheets are suspended on the members 54. When one is to be removed, the members 54 are turned in the direction of the arrow on Fig. 16, to the position indicated in dotted lines on Fig. 19, when it will be seen 125 that any sheet can be withdrawn by simply forcing the slots 53 over the members 54. When the members 54 are turned again to their normal position, all of the sheets are securely held in the file.

In Figs. 20 to 22, inclusive, a modification of the device is illustrated in which the hanger 12 is provided with rotatable V-shaped members 59 having projections 60 at their outer ends. This device is likewise adapted to co-operate with 135 sheets having openings and connecting slots as indicated in Fig. 23. The members 59 normally are maintained in the position indicated in Fig. 20. They may, however, be rotated to an angle of 180°, as indicated in Fig. 21, and when they 140 are in this position any desired sheet can be removed readily from the file. The relative positions of the members 59 are illustrated more clearly in Fig. 22.

All of the various modifications of the device as illustrated and described embody the principle upon which the invention depends, that is, the provision of projecting means on the hanger to receive and support a plurality of suspended sheets, the means being operable to per- 145 150

mit the detachment of any selected sheet without removing adjacent sheets. In each of the forms of the invention, any selected sheet can be separated and removed without disturbing substantially the remaining sheets and without varying the order in which the latter are arranged. The sheet removed can be returned as readily to its proper position in the file. Thus all of the sheets are accessible. In any of the forms of the device as illustrated and described the means for engaging the opening in the sheets can be tilted as illustrated in Fig. 2, to prevent the sheets from slipping therefrom.

The structure and arrangement are extremely simple. There are no complicated mechanical devices. Nevertheless the sheets in the file are firmly held and will not separate from the file until the co-operating parts are manipulated in the manner described. The sheets are suspended and may be protected from dust and dirt. They are not likely to be torn or disfigured, and they can be preserved, therefore, indefinitely in a satisfactory and usable condition.

Numerous details of construction and arrangement of the parts can be varied without departing from the invention or sacrificing any of the advantages thereof.

I claim:

1. A filing device for drawings and the like comprising a pivoted support, a hanger slidably mounted on the support, and spaced means projecting from the hanger and adapted to receive and support from the projecting portions a plurality of suspended sheets having openings therein to register with the spaced means, the latter being operable to permit the detachment of any selected sheet without removing adjacent sheets from the projecting means.

2. A filing device for drawings and the like comprising a pivoted support, a hanger slidably mounted on the support, and spaced means projecting from the hanger and adapted to receive and support from the projecting portions a plurality of suspended sheets having openings therein to register with the spaced means, the latter including co-operating members, certain of the members being operable to permit the detachment of any selected sheet without removing adjacent sheets from the projecting means.

50

3. A filing device for drawings and the like comprising a pivoted support, a hanger slidably mounted on the support, and spaced means projecting from the hanger and adapted to receive and support from the projecting portions a plurality of suspended sheets having openings therein to register with the spaced means, the latter including co-operating relatively movable members, certain of the members being operable to permit the detachment of any selected sheet without removing adjacent sheets from the projecting means.

80

4. A filing device for drawings and the like comprising a pivoted support, a hanger slidably mounted on the support, spaced means projecting from the hanger and adapted to receive and support from the projecting portions a plurality of suspended sheets having openings therein to register with the spaced means, the latter being operable to permit the detachment of any selected sheet without removing adjacent sheets from the projecting means, and means to normally lock the sheets on the spaced means.

90

5. A filing device for drawings and the like comprising a pivoted support, a hanger slidably mounted on the support, spaced means projecting from the hanger and adapted to receive and support from the projecting portions a plurality of suspended sheets having openings therein to register with the spaced means, the latter including co-operating members, certain of the members being operable to permit the detachment of any selected sheet without removing adjacent sheets from the projecting means, and means to normally lock the members.

100

6. A filing device for drawings and the like comprising a hanger and spaced means projecting from the hanger and adapted to receive and support from the projecting portions a plurality of suspended sheets having openings therein to register with the spaced means and slots extending from said openings to one edge thereof, said spaced means being rotatable and in one position adapted to prevent removal of the sheets while in another position being adapted to have any selected sheet withdrawn therefrom without removing adjacent sheets.
